ABSTRACT: A multipump fluid delivery system that simultaneously provides pump redundancy and the large displacement necessary at low startup speeds. Valve means are provided to cause one or more pumps to recirculate unpressurized fuel during normal operation when the entire flow of the several pumps need not be pressurized to meet system demands. The valve means automatically alternates the loaded pump each successive startup. This alternate loading tends to equalize wear among the several pumps, thereby affording a longer life before fuel system overhaul is required. The valve means also simultaneously serves a pressure relief function.

WEAR EQUALIZED FUEL DELIVERY SYSTEM

BACKGROUND OF THE INVENTION

Aircraft engine fuel pump systems generally produce more flow than required by the engine during normal flight. This is due in part to the addition of pump displacement in the form of independently operating pumps to achieve reliability by way of redundancy and in part to the need for a large flow during low speed pump operation, such as cranking, or during peak demand conditions, such as afterburning. In one form of prior art system the redundant pump is always producing flow at pressure; flow in excess of engine demand being returned to the unpressurized state with an associated waste of work of pressurization and fuel heating which increases the probability of cavitation in the system. An alternate form of prior art system has means therein to bypass the flow produced by the redundant pump so that the bypass flow is raised to system pressure only when part of the redundant pump output is needed to supplement flow from the "full time" pump or pumps to meet engine demand. The redundant pump in this alternate form of system is pressurized for only a fraction of its total operating time, and hence the system life between overhauls is controlled by the service life of the "full time" pump or pumps. It is apparent that if the redundant pump could be made to share the work load evenly with the "full time" pump, then the service life of the pumping system can be extended between overhauls.

SUMMARY OF THE INVENTION

The invention comprises a fuel pumping system having at least two pumps whenever engine fuel demand is significantly diminished, the pump to be unloaded being selected in turn according to a fixed valve sequence which insures that the number of unloading cycles imposed upon any pump will nearly equal the number of unloading cycles imposed upon any other of the several pumps.

It is an object of the invention to provide a fuel delivery system having a plurality of fixed displacement pumps; means to selectively bypass one or more of said pumps to effectively trim the displacement actually delivering pressurized fuel in response to fuel demand; and relief valve means integral with said selective bypass means, said relief valve means adapted to bleed flow from the engine supply conduit in response to excessive pressure therein.

It is a further object of the invention to provide a turbine engine fuel delivery system having a plurality of pumps therein; some of which may at any time have active status and others of which may at the same time have redundant status and means to selectively alter the status of said pumps such that pump pressurized duty cycle time will be statistically equally distributed among the several pumps for randomly generated engine runs.

These and other objects will become evident to those familiar with the fuel control art upon reading the following description made with respect to the associated drawings.

BRIEF DESCRIPTION OF THE DRAWINGS

FIG. 1 shows a circuit schematic of a fluid delivery system illustrative of the concept of the present invention.

FIG. 2 is a fragmented view partly in longitudinal section taken through the preferred form of the bypass selector of a fluid delivery system of the present invention, with the piston in the full downward position.

FIG. 3 is a transverse section taken along line 3-3 of FIG. 2.

FIG. 4 is a partial longitudinal section taken along line 4-4 of FIG. 2.

FIG. 5 is similar to FIG. 2 with the piston displaced upward from the full open or downward position.

DESCRIPTION OF THE PREFERRED EMBODIMENT

The present invention offers means to automatically alternate in fixed sequence the pump whose output is to be bypassed after each of a series of engine starts. While the description to follow is for simplicity made with reference to two pumping units, it will be apparent that by normal application of design skill a larger number of pumping units may be controlled by adding a larger number of ports and by correspondingly decreasing the angular advance of a single control piston utilizing the principles taught hereinafter. As shown in FIG. 1, this invention discloses structure utilizing a valve 32 having a control piston 40 axially and rotationally movably disposed in a housing 38, the piston 40 having a transverse passageway or bypass passage 46 therethrough. The piston is spring loaded to an axial shutoff position at which the transverse passageway 46 is not aligned with passageways in the valve housing and therefore flow through the valve does not occur. System discharge pressure sufficient to overcome the spring load is applied to one end 44 of the spool 40 to cause the piston to axially advance toward a downward or open position and simultaneously rotate to a discrete angular position at which the transverse passageway interconnects the inlet and discharge ports of one of a plurality of pumps thereby subtracting the flow produced by that pump from the rate of fuel flow previously delivered to the engine. A relief function is provided in the form of adjustably restricted passageways such as metering grooves 48 and 52 interconnecting the branch conduit 36 and inlet ports 19 of the pump actually delivering fuel to the engine at operating engine speeds so that the pump output is split between bypassed flow and engine consumption. Increased pressure causing further axial compression of the spring 56 does not further rotate the control piston, but rather places metering grooves 48 and 52 in communication with the load connected discharge conduit 36, thereby relieving pressure in that conduit by permitting fuel to bypass to inlet 19 in a relief valve functional mode. When the engine is shut down, the spring 56 axially resets the piston 40 and indexing means 62 simultaneously rotationally advance the piston 40 to another shutoff position. After the engine is again started, the piston is similarly axially and rotationally advanced to a different discrete position where a pump different from the previously bypassed pump is bypassed. A check valve 26 and 28 in the output line of each pumping unit prevents pressurized fuel from backflowing from engine connected pumping unit(s) to a pumping unit functioning in the bypass mode.

Referring to FIG. 1, fuel pumps 10 and 12 receive inlet flow from pump inlet conduits 16 and 18 respectively and discharge flow into pump discharge conduits 22 and 24 respectively, said discharge conduits merging into an engine intake or supply conduit 20. A pair of check valves 26 and 28 are respectively placed in pump discharge conduits 22 and 24 downstream of branch conduits 34 and 36 which supply flow to a bypass valve 32 from said pump discharge conduits. A signal pressure conduit 30 places valve 32 and engine intake conduit 20 in fluid communication to transmit system discharge pressure to the former. Pump inlet conduits 16 and 18 receive new flow from fuel tank 14 and intermittently receive recirculated flow from bypass valve 32 by way of valve discharge conduits 17 and 19.

Referring to FIG. 2, the selector valve, shown generally at 32, comprises a housing 38 having a control piston 40 axially slidably disposed in a bore 39 in said housing. O-ring seal 42 retained on the periphery of piston 40 seals a variable volume chamber 44 formed by the cooperation of housing 38 and piston 40. Piston 40 has an elongated passageway 46 positioned transversely therethrough and metering grooves 48, 50 and 52 formed thereon (48 and 52 in phantom). A second O-ring seal 54 is positioned on piston 40 in axially spaced apart relation with respect to seal 42 such that for any position assumed by piston 40, pressurized fluid conveyed to the interior of housing 38 by way of conduits 34 and 36 will be contained

between said O-ring seals so as not to produce a net axial thrust force acting to shift piston 40. Piston 40 is urged toward chamber 44 by helical spring 56 compressed between between an internal flange 37 integral with housing 38 and thrust bearing 58. Bearing 58 is positioned interjacent said spring and piston to minimize rotational friction and to prevent spring windup as piston 40 is rotated. Rotation of piston 40 occurs simultaneously with axial movement of the piston under the net influence of opposed axial forces caused by spring 56 and pressure in chamber 44 since a "T-bar" extension 60 of piston 40 engages a cam slot 61 of an indexing scroll 62 which is fixed against flange 37 by an end plug 41 threadably engaged with housing 38. Scroll 62 is split to permit installation of extension 60 therein at assembly. Section line 3-3 through conduits 36 and 19 provides orientation for FIG. 3, and section line 4-4 through extension 60 provides orientation for FIG. 4.

Referring to FIG. 3, flow in conduit 36 supplied by pump 12 appears to be blocked by piston 40, thereby sending the entire output of pump 12 to the engine by way of conduit 24 while the output of pump 10 is free to flow through conduit 34, elongated passageway 46 in piston 40, and back to pump inlet by way of conduit 17. Actually, the situation described would apply had FIG. 3 resulted from a section through FIG. 5, but in FIG. 3 grooves 48 and 52 are in fluid communication with conduits 36 and 19 respectively, thereby permitting relief flow between conduits 36 and 19 by way of groove 50 which does not appear in FIG. 5. This relief flow occurs only when pressure in chamber 44 causes extension 60 to approach the lower limit of travel permitted by cam slot 61 in indexing scroll 62. When piston 40 axially advances under the influence of pressure less than relief valve cracking pressure, rotary piston motion occurs simultaneously with the axial motion; however, the shape of cam slot 61 is such that no further rotational piston movement accompanies the downward axial piston movement under the influence of pressures in excess of the relief valve cracking pressure.

Referring to FIG. 4, indexing scroll 62 is held against flange 37 by threaded plug 41. Indexing scroll 62 comprises a split cylindrical sleeve having internal relief forming a cam slot 61 which confined the distal ends of T-bar 60 such that axial motion of piston 40 is accompanied by rotational motion thereof for a limited range of axial motion corresponding to discharge pressure having a magnitude lower than relief valve cracking pressure.

Referring to FIG. 5, spool 40 is seen to be axially shifted from the position occupied in FIG. 2. Since passageway 46 through piston 40 is elongated, flow passes freely from conduit 34 to conduit 17 in the bypass mode for both FIG. 2 and FIG. 5 positions. In FIG. 5, however, grooves 48 and 52 (phantom) are not in fluid communication with conduits 36 and 19, and it is apparent that when pressure in chamber 44 must increase to further compress spring 56 before pressurized fuel will dump to inlet by way of grooves 48 and 52 in a relief mode. It is also apparent that when pressure in chamber 44 diminishes permitting spring 56 to urge piston 40 upward, the acute angle of the scroll above T-bar extension 60 is offset from the centerline of said extension and will cause the piston to rotate clockwise, as viewed from chamber 44. The scroll is so designed that pressure cycles in chamber 44 will cause the piston to rotate clockwise, as viewed from chamber 44. The scroll is so designed that pressure cycles in chamber 44 will always produce unidirectional rotation of piston 40.

Reviewing the overall operation with reference to a two-pump system, the output of pump 10 and pump 12 is connected to valve 32 by conduits 34 and 36. The pressure in engine supply conduit 20 is transmitted by conduit 30 to chamber 44 and loads piston 40 against spring 56. As operating pressure is approached, piston 40 compresses spring 56 and, depending on the indexing of the control piston, will then bypass pump 10 or pump 12. As pressure continues to increase, the piston will continue to move downward, leaving for instance the pump 10 bypassed and controlling the relief pres-

sure by metering flow through grooves 48, 50 and 52. The control piston is indexed by the indexing scroll 62 which operates as a cam on T-bar 60 attached to control piston 40. Each time the engine is shut down, control spring 56 pushes control piston 40 upward, and T-bar 60 coacts with cam grooves 61 of scroll 60 to rotate the piston approximately 45°. When the engine is started, pressure in chamber 44 increases and moves the piston 40 downward and T-bar 60 cams along the bottom surface of indexing scroll cam groove 61 to rotate piston 40 an additional 45°. Therefore, each time the engine is restarted, the control piston will rotate a total of 90° to bypass first one pump and then the other. The indexing scroll cam slot top and bottom surfaces are offset sufficiently to always cause the control piston to rotate in one direction.

The disclosure set out has been made by way of illustration and is not intended to be exhaustive or limiting as to the inventive concept. I wish to avail myself of all variations and modifications which will be obvious to those versed in the aircraft engine fuel handling art.

I claim:

1. A fluid delivery system comprising:
a plurality of pumps, each of the said pumps having an inlet and an outlet;
a plurality of inlet conduits respectively connected to said pump inlets for delivering fluid thereto;
a plurality of discharge conduits respectively connected to said pump outlets for receiving discharge flow therefrom;
a supply conduit fluidly interconnecting said discharge conduits to receive discharge flow therefrom and deliver fluid at system discharge pressure to a using device; and
means automatically actuated by a predetermined decrease and subsequent predetermined increase in said system discharge pressure to bypass a discharge flow from each of said pumps in succession such that after each pressure cycle a pump different from the previously bypassed pump is bypassed.

2. A fluid delivery system, in accordance with claim 1, wherein said automatically actuated means comprises:
means to prevent reverse flows in said discharge conduits;
a selector valve, having a bypass passage, positionable in a plurality of discrete positions in which fluid is bypassed through said bypass passage from at least one of said discharge conduits to said pump inlets, the number of positions being at least equal to the number of said pumps;
a plurality of branch conduits fluidly interconnecting said respective discharge conduits and said selector valve, said branch conduits being fluidly connected to said discharge conduits at respective locations intermediate said preventing means and said outlets;
a pressure-sensing conduit fluidly interconnecting said selector valve and said supply conduit to transmit said system discharge pressure thereto;
means fluidly connecting said selector valve to said pump inlets; and
an automatic indexing device responsive to said system discharge pressure connected to said selector valve to successively position said selector valve in said discrete positions when said system discharge pressure decreases a predetermined extent and then increases a predetermined extent such that each of said pumps is successively bypassed via said bypass passage as said selector valve moves between said discrete positions.

3. A fluid delivery system, in accordance with claim 2, wherein said selector valve includes:
a housing having a bore therein and a plurality of pairs of inlet and outlet ports fluidly connected to said bore, the inlet and outlet port of each pair being respectively connected to one of said branch conduits and said pump inlet connecting means; and
a piston disposed in said bore to form a chamber fluidly connected to said supply conduit, said piston containing said bypass passage, said indexing device being operatively

connected to said piston to cause axial and rotational movement of said piston in said bore in response to changes in said system discharge pressure is brought into register with at least one of said pairs of inlet and outlet ports at a preselected magnitude of said system discharge pressure. 5

4. A fluid delivery system, in accordance with claim 3, wherein said piston comprises:

a groove adapted to fluidly communicate with at least another pair of inlet and outlet ports at another preselected magnitude of said system discharge pressure to thereby direct discharge flow from one of said pumps which is not being bypassed to said pump inlets. 10

5. A fluid delivery system comprising:

a plurality of pumps, each of said pumps having an inlet and 15 an outlet;

a plurality of inlet conduits respectively connected to the pump inlets for delivering fluid thereto;

a plurality of discharge conduits respectively connected to the pump outlets for receiving discharge flow therefrom; 20 a supply conduit fluidly interconnecting said discharge conduits to receive discharge flow therefrom;

a plurality of check valves respectively associated with said discharge conduits intermediate said supply conduit and said outlets for preventing reverse flows in said discharge conduits; 25

a selector valve, having a bypass passage, positionable in a plurality of discrete positions in which fluid is bypassed through the bypass passage from at least one of said discharge conduits to said pump inlets, the number of valve positions being at least equal to the number of pumps; 30

a plurality of branch conduits fluidly interconnecting said respective discharge conduits and said selector valve, said branch conduits being fluidly connected to said discharge conduits at respective locations intermediate said check valves and said outlets; 35

means fluidly connecting said selector valve to said pump inlets;

a pressure-sensing conduit fluidly interconnecting said selector valve and said supply conduit to transmit system discharge pressure to said selector valve; and

an automatic indexing device responsive to discharge pressure and connected to said selector valve to successively position said selector valve in said discrete positions when said system discharge pressure decreases a predetermined extent and then increases a predetermined extent such that each of said pumps is successively bypassed via said bypass passage as said selector valve moves between said discrete positions, said selector valve thereby serving to 50 equalize the wear between said pumps.

6. A fluid delivery system, in accordance with claim 5, wherein the selector valve includes:

a relief groove to direct discharge flow from one of said pumps which is not being bypassed to said pump inlets 55 when said system discharge pressure exceeds a predetermined value.

7. A fluid delivery system, in accordance with claim 5, wherein said selector valve includes:

a housing having a bore therein and a plurality of pairs of 60 inlet and outlet ports fluidly connected to said bore, the

inlet and outlet port of each pair being respectively connected to one of said branch conduits and said pump inlet connecting means; and

a piston disposed in said bore to form a chamber fluidly connected to said supply conduit, said piston containing said bypass passage, said piston to cause axial and rotational movement of said piston in said bore in response to changes in said system discharge pressure in said chamber such that said bypass passage is brought into register with at least one of said pairs of inlet and outlet ports at a preselected magnitude of said system discharge pressure. 8. A fluid delivery system, in accordance with claim 7, wherein said piston comprises:

a groove adapted to fluidly communicate with at least another pair of inlet and outlet ports at another preselected magnitude of said system discharge pressure to thereby direct discharge flow from one of said pumps which is not being bypassed to said pump inlets. 9. A fluid delivery system comprising:

at least two pumps, each of said pumps having an inlet and an outlet;

at least two inlet conduits respectively connected to said pump inlets for delivering fluid thereto;

at least two discharge conduits respectively connected to said pump outlets for receiving discharge flow therefrom;

a supply conduit fluidly interconnecting said discharge conduits to receive discharge flow therefrom and deliver fluid at system discharge pressure to a using device;

a valve housing having a bore therein and at least two inlet ports and at least two outlet ports in communication therewith;

means respectively fluidly interconnecting said inlet ports with said discharge conduits at respective locations intermediate said pump outlets and said preventing means;

means fluidly interconnecting said outlet ports and said pump inlets;

a piston mounted within said bore for sliding movement therein, said piston having a bypass passage and a groove, said passage adapted to fluidly interconnect one of said inlet ports with one of said outlet ports to bypass at least one of said pumps and said groove adapted to simultaneously fluidly interconnect the other of said inlet ports with the other of said outlet ports at certain piston positions, the area of communication between said groove and said other ports increasing as said piston slides within said bore in a predetermined direction;

means communicating said system discharge pressure to an end of said piston to drive said piston in said predetermined direction;

spring means urging said piston in the direction opposite to said predetermined direction to bias said piston against said system discharge pressure; and

means to rotate said piston within said bore during sliding movement of said piston in both said predetermined and opposite directions such that said bypass passage and said groove fluidly interconnect different inlet and outlet ports when said piston moves a certain distance opposite to said predetermined direction and then moves a certain distance in said predetermined direction.
